RAILWAY SIGNALING

George R. Pflasterer, Greenville, Pa., assignor to
The Union Switch & Signal Company, Swiss-
vale, Pa., a corporation of Pennsylvania

Application March 16, 1939, Serial No. 262,211

13 Claims. (Cl. 246—53)

My invention relates to railway signaling, and particularly to an arrangement involving wayside signals located along a trackway for governing the movement of trains.

One feature of my invention is the provision of novel and improved means for displaying a distinctive permissive indication at the entrance to an occupied block or stretch of track, so that a train may enter such block or stretch of track without stopping, and for displaying a stop indication if the permissive indication is not displayed when it should be.

I shall describe one form of railway signaling embodying my invention, and shall then point out the novel features thereof in claims.

The accompanying drawing is a diagrammatic view showing one form of railway signaling embodying my invention for the control of signals of a type, such for example as searchlight signals, having a mechanism operable to various positions for cooperating with a lamp to display corresponding indications.

Referring to the drawing, the reference characters 4 and 4a designate the rails of a stretch of railway track over which traffic normally moves in the direction indicated by the arrow, which I shall assume is the eastbound direction. Rails 4 and 4a are divided by insulated joints 5 into blocks a—b, b—c, etc.

Each of these blocks as shown is further divided by other insulated joints 5 into two sections, block a—b, for example, being divided into sections 1T and A!T. It is not necessary, for the purpose of my invention, that the blocks be divided as shown. In some instances it might be satisfactory to have only one section for each block, and in other instances it might be necessary to divide each block into more than two sections. Each track section is provided with a track circuit including a battery 6 connected across the rails adjacent one end of the section, and a relay, designated by the reference character TR with a distinguishing prefix, connected across the rails adjacent the opposite end of the section.

Adjacent the entrance end of each of the blocks, such as at a, b and c, a signal is located for governing eastbound traffic movements into the corresponding block. These signals are designated by the reference characters 1, 2 and 3, respectively. As here shown, each of the signals is of the searchlight type, but may be of any other suitable design.

Each of the signals as shown comprises a control member or mechanism 7 mounted to oscillate between two extreme positions, and controlled by

a control winding 8 and by a permanent magnet or an electromagnet not shown, so that when winding 8 is energized, member 7 will move to one of its extreme positions or the other according as winding 8 is energized by current of normal or reverse polarity. Member 7 is biased toward a middle position, which it occupies when winding 8 is deenergized. Member 7 carries three roundels G, R and Y arranged to cooperate with a signal lamp, designated by the reference character E with a numerical prefix corresponding to the reference character for its signal, in such manner that when member 7 is in the middle or stop position, roundel R is in front of lamp E, whereas 15 when member 7 is swung to the left or to the right into a caution or a proceed position, roundel Y or roundel G, respectively, is placed in front of lamp E.

As shown in the drawing, lamp E is above the roundels, but the lamp is placed in this location for purposes of illustration, and it is to be understood that in actual practice, the lamp is directly behind the roundels.

Each of the signals operates a contact 9, which 25 is closed when roundel Y is placed in front of lamp E, but is open when roundel G or R is placed in front of lamp E.

A signal of this type is disclosed and claimed in Letters Patent of the United States No. 1,864,224 30 granted to Wesley B. Wells on June 21, 1932, for Light signals.

Associated with each signal is a polarized signal relay designated by the reference character HD preceded by a number corresponding to the 35 reference character for its signal. The HD relays are of the retained neutral type, that is, the front contacts of these relays are slow to release, so that they do not open during an operation of the polar contacts of these relays from either extreme position to the other.

Also associated with each signal, are two neutral relays, comprising an approach control relay 40 designated by the reference character ER with a prefix corresponding to the reference character for its signal, and a checking relay of the slow release type designated by the reference character XR preceded by a number corresponding to the reference character for its signal.

Also associated with each signal, is a flasher relay 50 designated by the reference character F with a prefix corresponding to the reference character for its signal. Each of the flasher relays F is provided with contacts designated by the reference characters 11 and 12, respectively, which are biased toward the normal position in which they

are shown, when their relay F is deenergized, but which are periodically operated to the dotted line position, shown to the right of the normal position, when their relay F is energized. Each contact 11 is therefore constantly closed when the relay F by which it is operated is deenergized, and is periodically closed when its relay F is energized. Each contact 12 is open when its relay F is deenergized, but becomes closed periodically when its relay F is energized.

The winding 8 of each signal is energized by normal and reverse control circuits controlled by the associated signal relay HD, when the block for its signal, which is the first block in advance of its signal, is unoccupied or clear. Winding 8 of each signal is also energized by a second reverse control circuit controlled by a front contact of the associated checking relay and by back contacts of its signal relay when its block is occupied by a train.

The lamp E for each signal is lighted by a circuit which is controlled by a back contact of the associated approach control relay, when the next block in the rear of its signal is occupied, and by the contact 11 of the associated flasher relay F.

Each signal relay HD is energized only if the block for its signal is unoccupied, and is energized by current of normal or reverse polarity according as the HD relay for the next signal in advance is energized or deenergized.

Each approach control relay ER is energized by current of a given polarity in series with the signal relay HD for the next signal in the rear.

Each checking relay XR has a first energizing circuit controlled by a front contact of the associated approach control relay ER; a second energizing circuit controlled by a back contact of the associated approach control relay ER and by a front contact of the associated HD relay; and a third energizing circuit controlled by the contact 12 of the associated flasher relay F.

Each flasher relay F is energized when the first block in the rear and the first block in advance of its signal are both occupied and the member 7 of the associated signal is in the position in which, in conjunction with the lamp E for its signal, it displays a yellow indication on account of its roundel Y being in front of lamp E for its signal.

As shown in the drawing, track section 3T, immediately in advance of signal 3, is occupied by a train W. The indication displayed by each of the signals 1 to 3, inclusive, under this condition, when a second train occupies the next block in the rear of each of these signals successively, and the meanings of these indications are stated in the following table:

Signal	Indication displayed	Meaning of indication
1.....	Green	Proceed.
2.....	Constant yellow	Prepare to stop at next signal.
3.....	Flashing yellow	Proceed at restricted speed, block is occupied.
3.....	Constant red would be displayed instead of flashing yellow, if relay 3F should be falsely deenergized.	Stop and proceed.

With the apparatus arranged as shown in the drawing, each signal lamp E is lighted only when a train occupies the first block in the rear of the associated signal, and would, therefore, not be lighted with a train in only section 3T as shown. However, in order to facilitate an understanding of the operation of the system, each of the signal

lamps E is shown lighted as it would be lighted if a train occupied the first block in the rear of its signal while no other section shown in the drawing is occupied except section 3T, which is occupied by train W.

As shown in the drawing, when a first train occupies section 3T, signal 1 will display a constant green indication if a second train occupies section O1T in the rear of signal 1; signal 10 2 will display a constant yellow indication if the second train occupies the block a-b instead of section O1T; and signal 3 will display a flashing yellow indication if the second train occupies block b-c and flasher relay 3F is operating; or 15 signal 3 will display a constant red indication if flasher relay 3F should be falsely deenergized.

I shall now describe the manner in which these indications are displayed while a first train W occupies section 3T, as shown in the accompanying drawing, with a second train in the next block in the rear of the various signals.

With train W occupying section 3T, relay 3TR is deenergized and hence its contact 15 is open, thereby deenergizing relay 3HD. If, as shown in 25 the drawing, there is no train in block b-c, relays 3ER and 2HD will be energized by a circuit passing from terminal B of a suitable source of current, through the winding of relay 3ER, back point of contact 16 of relay 3HD, winding of relay 2HD, contact 15 of relay 2TR, contact 14 of 30 relay A2TR, and the back point of contact 13 of relay 3HD to terminal 0 of the same source of current. With relay 3ER thus energized, relay 3XR is energized by its first circuit, passing from terminal B, through the front point of contact 17 of relay 3ER, and the winding of relay 3XR to terminal 0. With relay 3XR thus energized, winding 8 of signal 3 is energized by current of reverse polarity passing from terminal B, through contact 19 of relay 3XR, back point of contact 22 of relay 3HD, winding 8 of signal 3, and back point of contact 23 of relay 3HD to terminal 0. With winding 8 thus energized by a reverse control circuit, roundel Y of signal 3 is in front of 35 lamp 3E, and hence contact 9 of signal 3 is closed. With relay 3ER energized, however, the circuit for energizing relay 3F is open at the back point of contact 17 of relay 3ER, and the circuit for energizing lamp 3E of signal 3 is open at contact 10 of relay 3ER.

Relay 2HD is energized by current of reverse polarity in the circuit previously traced for relays 3ER and 2HD. With relay 2HD thus energized, a circuit including relays 1HD and 2ER is completed for energizing relay 1HD by current of normal polarity, this circuit passing from terminal B, through the winding of relay 2ER, front point of contact 13 of relay 2HD, contacts 14 and 15 of relays A1TR and 1TR, respectively, winding of relay 1HD, and the front point of contact 16 of relay 2HD to terminal 0. With relay 2ER energized, relay 2XR is energized by a circuit which is similar to that previously traced for relay 3XR. With relay 2HD energized by current of reverse polarity, winding 8 of signal 2 is energized in the reverse direction by a circuit passing from terminal B, through contact 20 of relay 2HD closed in the right-hand position, front point of contact 22 of relay 2HD, winding 8 of signal 2, front point of contact 23 of relay 2HD, and contact 24 of relay 2HD closed in the right-hand position, to terminal 0. Roundel Y of signal 2 is therefore in front of lamp 2E. With relay 2ER energized, flasher relay 2F and lamp 2E are deenergized at the back

points of contacts 17 and 10, respectively, of relay 2ER.

With the winding of relay 1HD energized by current of normal polarity by the circuit traced for relays 1HD and 2ER, winding 8 of signal 1 is energized by current of normal polarity passing from terminal B, through contact 21 of relay 1HD closed in the left-hand position, front point of contact 23 of relay 1HD, winding 8 of signal 1, front point of contact 22 of relay 1HD, and contact 20 of relay 1HD closed in the left-hand position, to terminal 0. If there is no train in the next block to the rear of signal 1, relay 1ER will be energized, and hence relay 1XR will be energized by a circuit which is similar to the circuit previously traced for relay 3XR. With winding 8 of signal 1 energized by current of normal polarity, roundel G of signal 1 is in front of lamp 1E.

I shall assume that a second train enters the first block in the rear of signal 1, causing relay 1ER to become deenergized. With relay 1ER deenergized, contact 17 of this relay will be opened at its front point, and hence the first energizing circuit for relay 1XR will be opened. Relay 1XR will, however, now be energized by its second energizing circuit, passing from terminal B, through the back point of contact 17 of relay 1ER, front point of contact 18 of relay 1HD, and the winding of relay 1XR to terminal 0. With relay 1ER deenergized, a circuit is now completed for constantly lighting lamp 1E, this circuit passing from terminal B, through contact 10 of relay 1ER, contact 11 of flasher relay 1F, and lamp 1E to terminal 0. Signal 1 will therefore display a constant green or proceed indication.

I shall next assume that the second train passes signal 1, entering block a-b and deenergizing relay 1TR, contact 15 of which then opens, thereby deenergizing relays 1HD and 2ER. Relay 1HD, upon becoming deenergized, opens, at the front point of its contact 18, the second energizing circuit previously traced for relay 1XR. Relay 1XR, being of the slow releasing type, does not, upon becoming deenergized, permit its contact 19 to open immediately.

Relay 1HD, upon becoming deenergized, therefore completes a circuit for energizing winding 8 of signal 1 by current of reverse polarity, this circuit passing from terminal B, through contact 19 of relay 1XR, back point of contact 22 of relay 1HD, winding 8 of signal 1, and back point of contact 23 of relay 1HD to terminal 0. Member 7 of signal 1 will then move to the caution position, closing its contact 9 and thereby completing a circuit for energizing flasher relay 1F, passing from terminal B, through the back points of contacts 17 and 18 of relays 1ER and 1HD, respectively, contact 9 of signal 1, and the winding of relay 1F to terminal 0.

Contact 12 of relay 1F then periodically closes the third energizing circuit for relay 1XR before contact 19 of this relay has opened on account of its second energizing circuit having been opened. On account of relay 1XR being of a slow releasing type, contact 19 of this relay will be retained in its closed position during the open periods of contact 12 of relay 1F. The circuit previously traced for lighting lamp 1E will now be periodically opened at contact 11 of relay 1F, causing signal 1 to display the flashing yellow or permissive indication.

When the second train leaves section O-T, relay 1ER will again become energized and open

the circuits previously traced for energizing relay 1F and lamp 1E. Relay 1XR will now be retained in its energized condition by its first energizing circuit including the front point of contact 17 of relay 1ER.

With relay 2ER deenergized, the first energizing circuit for relay 2XR will be opened and its second energizing circuit will become closed, similarly to the corresponding circuits previously described for relay 1XR. With roundel Y of signal 2 in front of lamp 2E, contact 9 operated by signal 2 is closed, but the energizing circuit for flasher relay 2F is open at the back point of contact 18 of relay 2HD, and hence relay 2F is deenergized. With relays 2ER and 2F deenergized, lamp 2E for signal 2 will be lighted by a circuit which is similar to the circuit previously traced for lamp 1E of signal 1. Lamp 2E will therefore be constantly lighted, and signal 2 will display a constant yellow or caution indication.

I shall now assume that the second train passes signal 2 and enters block b-c, thereby deenergizing relays 2HD and 3ER. The reverse energizing circuit previously traced for winding 8 of signal 2 will now be opened at the front points of contacts 22 and 23 of relay 2HD, and the second reverse energizing circuit for this winding, which is similar to the reverse energizing circuit previously traced for winding 8 of signal 1, will be completed at the back points of contacts 22 and 23 of relay 2HD. The circuit for energizing relay 2F, which is similar to the circuit previously traced for relay 1F, will now be completed at the back point of contact 18 of relay 2HD. Signal 2 will then display the flashing yellow or permissive indication until the second train leaves block a-b.

With relay 3ER deenergized, the first energizing circuit traced for relay 3XR will be opened at the front point of contact 17 of relay 3ER, and the energizing circuit for relay 3F, which is similar to the circuit previously traced for relay 1F, will be completed at the back point of contact 17 of relay 3ER. Relay 3XR will now be retained in the energized condition by its third energizing circuit including contact 12 of relay 3F. Lamp 3E will be periodically lighted, and signal 3 will thus display the flashing yellow or permissive indication.

If, for any reason, flasher relay 3F should be falsely deenergized, causing its contact 11 to remain constantly closed and its contact 12 to remain constantly open, relay 3XR will become deenergized, thereby opening, at its contact 19, the circuit for energizing winding 8 of signal 3 in the reverse direction, and causing roundel R of signal 3 to be moved in front of lamp 3E. With relays 3ER and 3F deenergized, lamp 3E will be lighted by a circuit which is similar to the circuit traced for lamp 1E, and hence signal 3 will display a constant red indication.

From the foregoing description and the accompanying drawing, it follows that in railway signaling apparatus embodying my invention, I have provided means for controlling a signal for governing traffic movements into a given block, section, or stretch of railway track, to display a constant indication for authorizing a traffic movement to be made into the associated portion of track, to display a flashing indication if the associated portion of track is occupied and the signal mechanism occupies a position for authorizing a traffic movement into the portion of track, and to display a constant stop indication if the flashing means should be falsely deener-

gized while the associated portion of track is occupied.

Although I have herein shown and described only one form of railway signaling embodying my invention, it is to be understood that various changes and modifications may be made therein within the scope of the appended claims without departing from the spirit and scope of my invention.

Having thus described my invention, what I claim is:

1. In combination, a stretch of railway track divided into blocks, a signal for each of said blocks comprising a signal lamp and a signal mechanism biased toward a stop position but operable to a proceed and a caution position for cooperating with said signal lamp for governing traffic movements into the associated block when said signal lamp is lighted, a signal relay for each of said signals, train responsive means for energizing each of said signal relays only if the block for the associated signal is unoccupied and for energizing each of said signal relays by current of normal or reverse polarity according as the next block in advance of the block for the associated signal is unoccupied or occupied, an approach control relay for each of said signals energized in series with the signal relay for the next signal in the rear, a checking relay for each signal, a circuit controlled by a front contact of each approach control relay for energizing the checking relay for the same signal, a second circuit controlled by a back contact of each approach control relay and by a front contact of the signal relay for the same signal for energizing the checking relay for the same signal, a flasher relay for each signal having a normal contact constantly closed while its flasher relay is deenergized and periodically closed while its flasher relay is energized and having a reverse contact which is periodically closed while its flasher relay is energized, a third circuit for energizing each checking relay controlled by the reverse contact of the flasher relay for the same signal, a circuit for energizing each of said flasher relays controlled by a back contact of the approach control relay and by a back contact of the signal relay for the same signal and also by a contact closed by the mechanism of the same signal when such mechanism occupies the caution position, a circuit for lighting the lamp for each signal controlled by a back contact of the approach control relay and the normal contact of the flasher relay for the same signal, means controlled by the signal relay for each signal when energized by current of normal or reverse polarity for operating the mechanism for the same signal to the proceed or the caution position respectively, and means controlled by a front contact of the checking relay for each signal for operating the mechanism for its signal to the caution position while the associated signal relay is deenergized.

2. In combination, a stretch of railway track divided into blocks, a signal for each of said blocks comprising a signal lamp and a signal mechanism for cooperating with said signal lamp when said signal lamp is lighted for governing traffic movements into the associated block, a slow release checking relay for each of said signals, a flasher relay for each of said signals having a normal contact constantly closed while the corresponding flasher relay is deenergized and periodically closed while the corresponding flasher relay is energized and having a reverse contact

which is periodically closed while the corresponding flasher relay is energized, traffic responsive means for energizing each checking relay if there is no train in the next block in the rear of the associated signal or if there is no train in the block for the associated signal while the next block in the rear is occupied, means for each signal controlled by the reverse contact of its flasher relay for also energizing its checking relay, traffic responsive means for conditioning the signal mechanism of each signal for cooperating with its lamp for displaying an indication for authorizing traffic movements into its block if its block is unoccupied, means for each signal controlled by a front contact of its checking relay and by traffic responsive means for also conditioning its mechanism for cooperating with its lamp for displaying a permissive indication if its block is occupied, traffic responsive means and means controlled by the mechanism of each signal for energizing the flasher relay for the corresponding signal when the first block in advance and the first block in the rear of the corresponding signal are both occupied, and means controlled by the normal contact of each flasher relay and by traffic responsive means for lighting the lamp for the associated signal when the next block in the rear is occupied.

3. In combination, a stretch of railway track divided into blocks, a signal at the entrance end of each of said blocks comprising a signal lamp and a signal mechanism operable to various positions for cooperating with said signal lamp to display various indications for governing traffic movements into the associated first block in advance, a flasher relay for each of said signals each having a first contact constantly closed while its flasher relay is deenergized and periodically closed while its flasher relay is energized, a second contact operated by each of said flasher relays each periodically closed while its flasher relay is energized, a slow release checking relay for each of said signals, traffic responsive means for energizing each of said checking relays while the block for the associated signal is clear, a circuit for each signal controlled by the second contact of its flasher relay for also energizing its checking relay, means controlled by traffic conditions in advance of each signal for operating the mechanism for each signal to a first or a second position according as the first two blocks in advance of the corresponding signal are clear or the first block in advance is clear while the second block in advance is occupied, means for each signal controlled by a front contact of its checking relay and by traffic conditions for also operating its mechanism to the second position if the first block in advance of the signal is occupied, means controlled by a contact of each signal closed while the mechanism for the corresponding signal occupies the second position and controlled by traffic conditions for energizing the associated flasher relay while the first block in advance of the corresponding signal is occupied, and means for each signal controlled by the first contact of its flasher relay for lighting its lamp.

4. In combination, a stretch of railway track divided into blocks, a signal for each of said blocks comprising a signal lamp and a signal mechanism operable to various positions for cooperating with said lamp to display various indications for governing traffic movements into the associated block, means controlled by traffic conditions for operating each of said signal

mechanisms to a given position for authorizing traffic movements into the associated block if the associated block is unoccupied, train responsive apparatus associated with each of said blocks, means for energizing said train responsive apparatus if the associated block is occupied, means controlled by said train responsive apparatus for operating the mechanism for each signal to a permissive position while the associated block is occupied, means controlled by traffic conditions for constantly lighting the lamp for each signal while the associated block is clear, and means controlled by said train responsive apparatus for periodically lighting the lamp for each signal while the associated block is occupied.

5. In combination, a stretch of railway track divided into blocks, a signal for each of said blocks for governing traffic movements into the associated block, control means for each of said signals, means controlled by traffic conditions for energizing the control means for each of said signals in a given manner if the next two blocks in advance of the corresponding signal are unoccupied and for energizing the control means for each of said signals in a second manner if the first block in advance is unoccupied but the second block in advance is occupied, means controlled by a train upon passing each of said signals for also energizing the control means for the corresponding signal in said second manner, and means controlled by the control means for each of said signals and by traffic conditions for controlling the corresponding signal to display a constant indication if its control means is energized in said first or said second manner while the first block in advance is unoccupied and for controlling the corresponding signal to display a periodic indication if the control means is energized in said second manner while the first block in advance is occupied.

6. In combination, a stretch of railway track divided into blocks, a signal for each of said blocks comprising a signal lamp and a signal mechanism operable to various positions for cooperating with said signal lamp to display various indications for governing traffic movements into the associated first block in advance of the corresponding signal, means controlled by traffic conditions for operating each of said signal mechanisms to a proceed position or a caution position according as the first two blocks in advance of the corresponding signal are clear or the first block in advance is clear while the second block in advance is occupied, a checking relay for each of said signals, means responsive to traffic conditions for energizing each said checking relay while either the first block in the rear of its signal or the first block in advance of its signal is clear, means controlled by each of said signal mechanisms and by traffic conditions for energizing the associated checking relay if its signal mechanism occupies the caution position while the first block in the rear of its signal and the first block in advance of its signal are both occupied, means controlled by a front contact of each checking relay and by traffic conditions for retaining the associated signal mechanism in the caution position while a train occupies the first block in advance of the corresponding signal after entering this block while its signal mechanism is in the caution position, and means controlled by each of said signal mechanisms and by traffic conditions for constantly lighting the associated signal lamp while

the first block in advance of its signal is clear and for periodically lighting the associated signal lamp while the first block in advance of its signal is occupied.

5 7. In combination, a stretch of railway track divided into blocks, a signal for each of said blocks comprising a signal lamp and a signal mechanism operable to various positions for cooperating with said lamp to display various indications for governing traffic movements into the associated block, means controlled by traffic conditions for operating each of said signal mechanisms to a first or a second position for authorizing traffic movements into its block according to its block and the next block in advance of its block are both clear or its block is clear and the next block in advance is occupied, means controlled by traffic conditions for also operating each of said signal mechanisms to its second position if its block becomes occupied, means controlled by each of said signals for retaining its mechanism in the second position while its block is occupied, and means controlled by each of said signals and by traffic conditions for constantly lighting the lamp for the corresponding signal while its block is clear and for periodically lighting the same lamp while its block is occupied and its signal mechanism is in said second position for authorizing traffic movements into its block.

20 8. In combination, a stretch of railway track including a given block, a signal for governing traffic movements into said block, signal control means for said signal, means controlled by traffic conditions for energizing said signal control means while said block is unoccupied, a slow release checking relay and a flasher relay, a circuit for energizing said checking relay including a contact closed if said block is unoccupied, a second circuit for energizing said checking relay closed if said flasher relay is energized, means controlled by a front contact of said checking relay and by traffic conditions for energizing said signal control means if said block is occupied, a circuit for energizing said flasher relay closed by said signal control means in its energized condition while said block is occupied, and means controlled by said flasher relay for controlling said signal to display a constant indication while said block is unoccupied and for controlling said signal to display a periodic indication if said block is occupied while said signal control means is energized.

45 9. In combination, a stretch of railway track including a given block, a signal comprising a signal lamp and a signal mechanism operable to authorizing and stop positions for cooperating with said lamp to display indications for authorizing traffic movements into said block or for stopping such traffic movements respectively, means controlled by traffic conditions for operating said signal mechanism to an authorizing position while said block is clear and for conditioning said mechanism for also occupying an authorizing position after a train enters said block, means controlled by said signal mechanism and by traffic conditions for constantly lighting said lamp if said block is unoccupied or if said signal mechanism occupies its stop position and for periodically lighting said lamp if said block is occupied while said mechanism is in an authorizing position, and means associated with the control for said lamp for deenergizing said mechanism if said lamp is controlled to be constantly

lighted when it should be periodically lighted while said block is occupied.

10. In combination, a stretch of railway track including a first and a second block, a signal comprising a signal lamp and a signal mechanism biased toward a stop position when deenergized but operable to a proceed or a caution position when energized for cooperating with said signal lamp for governing traffic movements into said first block when said signal lamp is lighted, train responsive means for energizing said signal mechanism for effecting its operation to said proceed or said caution position according as said first and second blocks are both unoccupied or said first block is unoccupied while said second block is occupied and for conditioning said mechanism to also occupy said caution position when said first block is occupied, train controlled lighting means for constantly lighting said lamp while said mechanism occupies its proceed or its stop position and also when said mechanism occupies its caution position while said first block is unoccupied but for periodically lighting said lamp when said mechanism occupies its caution position while said first block is occupied, and means controlled in conjunction with said lighting means for deenergizing said signal mechanism if said lighting means is controlled to constantly light said lamp when it should be controlled to periodically light said lamp while said first block is occupied.

11. In combination, a stretch of railway track including a given block, a signal comprising a signal lamp and a signal mechanism operable to a plurality of positions for cooperating with said lamp to display various indications for governing traffic movements into said block, means controlled by traffic conditions for operating said signal mechanism for authorizing traffic movements into said block while said block is clear, means controlled by traffic conditions as a train enters said block for operating said signal mechanism to a given position for authorizing traffic movements into said block, means controlled by said signal mechanism after being operated to said given position for retaining said signal mechanism in said given position while a train occupies said block, and means controlled by said signal mechanism and by traffic conditions for constantly lighting said lamp if said block is unoccupied and for periodically lighting said lamp if said block is occupied while said mechanism is in said given position for authorizing traffic movements into said block.

12. In combination, a stretch of railway track including a given block, a signal comprising a signal lamp and a signal mechanism capable of being conditioned for cooperating with said lamp to display various indications for governing traffic movements into said block, means controlled by traffic conditions in said block for conditioning said signal mechanism for authorizing traffic

movements into said block, a slow release checking relay, a circuit responsive to traffic conditions in said stretch closed only if said block is unoccupied for energizing said checking relay, a circuit controlled by a front contact of said checking relay for conditioning said signal mechanism for also authorizing traffic movements into said block when said block becomes occupied, a flasher relay, a circuit controlled by traffic conditions and by said signal mechanism for energizing said flasher relay if said block is occupied while said signal mechanism is in a condition for authorizing traffic movements into said block, a second circuit for energizing said checking relay closed by said flasher relay while said flasher relay is energized, and a circuit controlled by said flasher relay for constantly lighting said lamp while said flasher relay is deenergized and for periodically lighting said lamp while said flasher relay is energized.

13. In combination, a stretch of railway track divided into a first and a second section, a signal comprising a signal lamp and a signal mechanism capable of being conditioned for cooperating with said lamp to display various indications for governing traffic movements from said first section into said second section, train responsive apparatus for said first section, train responsive apparatus for said second section, means controlled by said train responsive apparatus for said second section for conditioning said signal mechanism for authorizing traffic movements into said second section if said second section is unoccupied, a checking relay, a circuit controlled by said train responsive apparatus for said first section for energizing said checking relay if said first section is unoccupied, a second circuit controlled by said train responsive apparatus for said first and second sections for energizing said checking relay if said first section is occupied while said second section is unoccupied, a flasher relay, a third circuit controlled by said train responsive apparatus for said first and second sections and by said signal mechanism for energizing said flasher relay if said second section is occupied while said first section is occupied and said signal mechanism is in a condition for authorizing traffic movements into said stretch, a fourth circuit controlled by said flasher relay for energizing said checking relay while said flasher relay is energized, means controlled by a front contact of said checking relay and by said train responsive apparatus for said second section for conditioning said signal mechanism for authorizing traffic movements into said second section while said second section is occupied, and means controlled by said flasher relay for constantly lighting said lamp while said flasher relay is deenergized and for periodically lighting said lamp while said flasher relay is energized.

GEORGE R. PFLASTERER.
